UNITED STATES PATENT OFFICE

114,586

DESIGN FOR A RIDGE CUTTER FOR ENGINE CYLINDERS

Eliot D. Green, San Francisco, Calif.

Application June 7, 1937, Serial No. 69,710

Term of patent 14 years

To all whom it may concern:

Be it known that I, Eliot D. Green, a citizen of the United States of America and resident of the city and county of San Francisco, State of California, have invented a new, original, and ornamental Design for a Ridge Cutter for Engine Cylinders, of which the following is a specification, reference being had to the accompanying drawing, forming, part thereof.

In the drawing, Fig. 1 is a perspective view of a ridge cutter for engine cylinders, showing my new design, taken from an angle slightly above

the plane of the base thereof and looking toward the cutter wheel.

Fig. 2 is perspective view taken from a point slightly higher, and with the device rotated approximately 45°.

Fig. 3 is a perspective view, looking down on the device.

I claim:

The ornamental design for a ridge cutter for engine cylinders, substantially as shown.

ELIOT D. GREEN.
